SHIM PLATE

Erik Gustaf Nylander, Chicago, Ill., assignor to
Holland Company, a corporation of Illinois

Application May 3, 1937, Serial No. 140,445

7 Claims. (Cl. 105—197)

This invention relates to railway trucks, and more particularly to means for maintaining required coupler heights by compensating for wear between center plates, wear on the wheel treads and other truck and car parts.

One of the objects of the invention is the provision of new and improved means for elevating the bolsters of railway trucks for maintaining the couplers of the cars at a predetermined height above the rails.

A further object of the invention is the provision of a new and improved metallic shim adapted to be employed in connection with a spring assembly for vertically adjusting the bolster of a railway truck, whereby the coupler may be maintained at a predetermined height.

A further object of the invention is the provision of a new and improved sectional shim together with novel means for securing the sections in position beneath the truck bolster.

A further object of the invention is the provision of a new and improved shim member that is simple in construction, inexpensive to manufacture, efficient in operation, easily and readily applied, and that may be firmly held in position when applied.

Other and further objects and advantages of the invention will appear from the following specification and accompanying drawings, in which—

Fig. 1 is a side elevation of a railway truck, with parts broken away, parts in section, and parts omitted for the sake of clearness, showing the invention in position therein;

Fig. 2 is a section on the line 2—2 of Fig. 1;

Fig. 3 is a section on the line 3—3 of Fig. 1;

Fig. 4 is a plan view of a modified form of the invention; and

Fig. 5 is a detail sectional view showing the use of a plurality of shims.

After being in use for some time, wear between center plates, wear on wheel treads, together with the wear on other parts of the car, results in the permanent lowering of the superstructure, and with it the coupler. In order to meet the requirements of the A. A. R. regulations, it is necessary either to renew the parts or to provide some means for elevating the coupler to the required height above the rails.

The present invention seeks to remedy this difficulty by the latter method, by providing means that may be readily and easily applied with a minimum amount of time and labor, and without dismantling or removing the spring assembly.

Referring now to the drawings, the reference

character 10 designates a side frame of a railway truck having a bolster opening 11 therein, in which is vertically slidable the end of the bolster 12, which in turn is supported by a spring assembly 13 in an enlargement of the lower portion 5 of the opening 11. The bolster 12 is provided with guides 14, which slidably engage the columns 15 at each side of the opening 11, as is usual in such constructions.

The lower portion 16 of the side frame 10 10 beneath the opening 11 is provided with integral flanges 17 and 18 (Fig. 2), extending laterally in a horizontal plane, and, together with the upper edge of said portion 16, form a support or seat 19 for the spring assembly 13. 15

The spring assembly 13 is adapted to be inserted between the bolster 12 and the spring seat 19. This assembly comprises a lower spring plate 21, an upper spring plate 22, and a plurality of springs 23 between the two plates. The spring plates 21, 22 may be, and preferably are, duplicates of each other and are somewhat in the form of a four leaf clover.

In the form of the device shown, the lower spring plate 21 is provided with downwardly extending projections 24 that engage corresponding openings 25 in the support or seat 19 for positioning said plate and spring assembly. In the construction shown, there are two of these projections on each plate, an inner one and an outer 30 one. The seat or support 19 may also be provided with upwardly extending projections 26, Fig. 1, which extend upwardly through corresponding openings 27 in the spring plate 21 for interlocking the parts together. On some side frames, these 35 projections are omitted. On such structures, the shims and spring plates need not have the corresponding openings. If desired, the spring plate 21 may be provided with a circular flange 20, extending about the opening 27. 40

Any suitable number of springs are employed. In the form of construction shown, in Fig. 3, the arrangement is such that five springs are used, one at each corner of the spring group and one in the center. The springs 23, of which 45 there are four, are of the conventional free acting helical type, and are seated at the corner portions of the plate 21. If desired, inner helical springs 30 may also be employed, as shown in Fig. 1. 50

The central load-supporting spring 29, Fig. 1, is preferably, though not necessarily, of the snubber type, whereby harmonic action of the spring assembly is prevented. The plate 21 may, if desired, be provided with suitable flanges 31 which 55

extend partially around the springs 23 on the outer sides thereof, for positioning the same on the plate. The upper spring plate 22 is substantially a duplicate of the lower spring plate and 5 similar parts are designated by the same reference characters. The projections 24 on the upper plate 22 are adapted to engage in recesses 32 in the bolster 12 when the assembly is newly installed.

10 Since the details of the spring assembly constitute no part of the present invention, except as described above, a further description of this assembly is not thought necessary.

It is common in present practice, especially in 15 trucks where the springs are supported on seats integral with the side frame, to employ a spring assembly in which the overall width of the same is greater than the distance between the columns 15, as shown in Fig. 2. In order to remove the 20 spring assembly from the side frame of such a construction it is necessary to elevate the bolster a sufficient distance for removing the springs, after which the plates may be removed by tilting or elevating the front or rear end so that they 25 will take a diagonal position across the bolster opening. This is necessary because the distance between the columns 15 is less than the overall width of the plate, as clearly shown in Fig. 2 of the drawings.

30 When, after continued use, the spring assembly does not support the bolster 12 at a sufficient height to maintain the coupler at the required distance from the rail, suitable means are inserted between the top plate 22 and the bolster 12. 35 It is desirable that this means be so constructed that it may be inserted without removing or disturbing the spring assembly, and at the same time be provided with means whereby it will be retained in position when inserted between the bolster and the top spring plate. Such a construction will now be described.

In the form of construction shown in Fig. 2, shim plates 33 are employed for this purpose. These plates are so constructed that they correspond in shape to the spring plate 22, except that 45 they are not provided with flanges for engaging the springs 13. The plate is provided with upwardly extending projections 34, more or less cone shape, which are formed by punching the metal upward, as shown in Fig. 3, to form recesses 35 on the lower side and projections 34 on the upper side. These projections are adapted to engage in the openings 32 on the under surface of the bolster 12, and the recesses 35 are 50 adapted to receive the projections 24 on the spring plate 22. These shims may be provided with downwardly extending projections 37, which may be formed by punching the metal downwardly, forming the recesses 38 on the upper side and the projections 37 on the lower. The projections 55 37 are of such diameter as to engage in the openings 27 in the top spring plate 22.

These shim plates may be inserted either between the spring plate 22 and the bolster 12, or 60 they may be inserted between the spring assembly and the seat portion 19 of the truck frame. If inserted below the lower spring plate, the shim may be in the form of a unitary structure because the lower portion of opening 11 below the bolster 70 and above the truss flanges 40 is enlarged for receiving the spring plate as clearly shown in Fig. 1 and the dimensions of this enlargement are such as to receive the shim without tilting if the springs be first removed. The shim plate may 75 be inserted above the truss flanges 40 and dropped

in position. But, if inserted between the lower spring plate and the seat 19, the springs must be removed or the assembly must be lifted with the bolster and the springs more or less compressed. This is objectionable because of the numerous parts to maintain in proper position during the operation. On the other hand, if it be made in sections, means must be provided for holding the sections in position.

As shown, the shim plate 33 is made in sections, divided along the line 39-41, Fig. 1, which is somewhat diagonal and leaves one of the projections 34 on one section and the other projection 34 on the other section. In order to insert the shim in position beneath the bolster 12, it is 10 only necessary to elevate the bolster and then put one of the sections in position with the projection 37 in the openings 27 of the spring plate 22 and the projection 24 of the spring plate in the recess 32 in the shim and then place the other 15 section in position in like manner. The bolster is then lowered and the openings 32 therein will engage the projections 34 on the shim for locking the parts together. It will thus be seen that each 20 shim plate section will be interlocked at three 25 different points with the spring plates 22 and that the interlocking portions 32, 34 of one plate are arranged opposite those of the other whereby when the sections are assembled, these interlocking 30 members cooperate to rigidly hold the assembled 35 shim plate in position on the upper spring plate 22. It will also be seen that the assembled shim plate sections and upper spring plate will function as a unitary rigid plate of increased thickness and will be held in position beneath the bolster by the two interlocking connections shown at 32, 34. If further elevation is necessary, a second shim 41, Fig. 5, which is a 40 duplicate of the shim 33, is inserted between the shim 33 and the bolster 12 and the parts will interlock in a similar manner as shown in Fig. 5. Additional shims may be inserted in the same manner, if required, or until the coupler has been elevated to the desired height.

In Fig. 4 of the drawings, is shown a modified 45 form of shim in which the parts are interlocked together. In this form of construction, the shim 42 is divided into two sections 43 and 44, divided along the line 45-46, longitudinally of the bolster. The line 45-46 divides the plate so that one of the projections 34' is on one section and the other projection 34' on the other section. Furthermore, the meeting edges are such as to form a head 47 on one section which is adapted to engage in a corresponding recess 48 in the 55 other section, the head and recess being of such a form that when they engage, they prevent separation of the sections by movement in the plane of the sections. Furthermore, the heads 47 are arranged opposite the corresponding projections 60 34' as clearly shown in Fig. 4 of the drawings. The shim is applied in the manner stated above.

While the spring plates 21 and 22 may be of the conventional contour, it is understood that the shape or contour of the same may be changed, 65 as for instance, the central portion may have raised or depressed portions for positioning the central spring. But for simplicity of description, they are shown and described as being duplicates and the shims have corresponding projections 70 and depressions so that the shim plates will nest with the spring plates, as shown in Figs. 1 and 3.

It will be seen from an inspection of Fig. 2 that the interlocking projection 37 and depression 38 on each shim section may be omitted, if desired, 75

since the projections 34 and corresponding recesses 35 will anchor the shim sections and the columns 15, 15 will prevent their rotation in either direction.

5 It is thought from the foregoing taken in connection with the accompanying drawings that the construction and operation of my device will be apparent to those skilled in the art and that changes in size, shape, proportion and details 10 of construction may be made without departing from the spirit and scope of the appended claims.

I claim as my invention:

1. A metallic sectional shim for use on railway trucks comprising a plurality of seating sections, 15 means on each section for interlocking said sections together, and means for connecting each section, against displacement, to both the conventional bolster and spring plate of a railway truck.

2. In a railway truck, a side frame having a 20 bolster opening and a spring seat in said opening, a bolster extending into said opening, a spring assembly including a spring plate between said bolster and seat, and a shim between said bolster and plate and interlocked therewith, said 25 shim comprising a plurality of sections interlocked with each other.

3. In a railway truck, a side frame having a 30 bolster opening and a spring seat within said opening, a bolster extending into said opening, a spring assembly between said bolster and seat, and a shim between said bolster and assembly, said shim comprising a plurality of sections, each section being interlocked with both the bolster and the assembly, and means for detachably connecting said sections together.

4. In a railway truck having a side frame provided with an opening, a bolster extending into said opening, columns for guiding the vertical movement of said bolster, a spring seat on said 40 frame beneath said bolster, a spring assembly between said bolster and seat, a spring plate between said bolster and spring assembly, a sectional metal shim between said plate and bolster extending between said columns, said shim having 45 its maximum dimensions longitudinally of said side frame at the inner and outer sides of said columns greater than the distance between said

columns whereby said columns will retain said shim in position beneath said bolster, cooperating interengaging means between said sections and between each of said sections and said assembly and spring plate.

5. In a railway truck, a side frame having a bolster opening, a bolster extending into said opening, a spring assembly for supporting said bolster from said side frame, a shim between said spring assembly and bolster and having 10 means for interlocking with the conventional interlocking means on said bolster and spring assembly, said shim being split along a diagonal line extending transversely of the truck so that a portion of said interlocking means is carried by 15 each shim section.

6. In a railway truck, a side frame having a bolster opening, a column at each side of said opening, and a spring seat within said opening, a bolster extending into said opening, a spring 20 assembly between said bolster and seat, said assembly comprising a plurality of springs, a spring plate engaging the upper ends of said springs, and a sectional shim between said assembly and bolster, said shim when assembled beneath said 25 bolster being of greater linear dimension longitudinally of said frame along lines extending parallel with said frame on the inner and outer sides thereof than the distance between said columns, each of said shim sections having an interlocking 30 connection with said bolster and with said spring plate.

7. In a railway truck, a side frame having an opening therein and columns at each side of said opening, a spring assembly seat, a spring assembly 35 within said opening and supported on said seat, said assembly comprising a plurality of springs, a spring plate engaging the upper ends of said springs, a bolster extending between said columns and supported on said assembly, the 40 widths of said assembly inwardly and outwardly of said columns being greater than the distance between said columns, a sectional shim between said assembly and bolster, and means for interlocking each of the shim sections with said bolster 45 and said spring plate and with one another.

ERIK G. NYLANDER.
